(57) **CLAIM**

The ornamental design for a work center with sink, as shown and described.

DESCRIPTION

FIG. 1 is a top, front, right perspective view of a work center with sink of our design;

FIG. 2 is a top, front, right perspective view of the work center with sink of FIG. 1 shown in an alternate position of the covers;

FIG. 3 is a top, front, right perspective view of the work center with sink of FIG. 1 shown in a second alternate position;

FIG. 4 is a top plan view thereof;

FIG. 5 is a bottom view thereof;

FIG. 6 is a front elevational view thereof;

FIG. 7 is a rear elevational view thereof;

FIG. 8 is a right side elevational view thereof; and,

FIG. 9 is a left side elevational view thereof.

The broken lines shown are for illustration purposes only and form no part of the claimed design.
